Nelson P. Howard

UNITED STATES PATENT OFFICE

GEORGE C. THOMAS, OF SWAMPSCOTT, MASSACHUSETTS, ASSIGNOR TO FITZ-EMPIRE DOUBLE PIVOT LAST COMPANY, OF AUBURN, MAINE, A CORPORATION OF MAINE

HINGE LAST

Application filed November 18, 1921. Serial No. 516,194.

This invention relates to collapsible lasts, and is disclosed in connection with an impos-
5 itive lock last, that is, a last which can be collapsed by pressure alone but which offers to collapse a definite and increasing resist-
10 ance over a short distance from the ex-
tended position. Lasts of this type require some sort of resilient structure to furnish the yielding resistance. The invention of H. W.
15 Lucas described and claimed in his applica-
tion Ser. No. 514,722, filed Nov. 12, 1921,
greatly simplifies previously known construc-
tions by providing for this purpose a resil-
ient bar or pin which is slightly bent by the
20 stresses incident to collapse and extension. It is a principal object of the present invention still further to improve this type of last without sacrificing any of the advantages gained by the invention mentioned. To this end, a feature of the invention consists in a resilient hinge or anchor pin, arranged to be deformed preferably by a bonding member as the last collapses or extends. A very simple, cheap construction is thus provided
25 which necessitates the removal of little wood from the last and is therefore of superior strength.

This and other features of the invention, including certain details of construction and
30 combinations of parts will be best under-
stood from the following description of a preferred embodiment selected for purposes of illustration and shown in the accompan-
ying drawings, and will then be pointed out in the claims.

In the drawings,

Fig. 1 is a side elevation, partly broken away, of the last in operative position;

Fig. 2 is a similar view of the last in col-
40 lapsed position;

Figs. 3, 4 and 5 are perspective views of three different forms of pins.

The forepart 10 and heel part 12 are severed by a line of cut having a convenient shape permitting relative movement of the parts for collapsing purposes. It is preferably shaped to comprise an approximately arcuate portion
45

14, abutting shoulders 16 at the bottom of the last and an open portion 18 at the top, as will be well understood by those skilled in the art.

The parts are joined by a link 20 pivoted on pins 22 and 24 in the heel part and forepart, respectively. One of these pins as 24, (or both, if desired) has a notch, or reduced portion at 25 between its ends which themselves 55 preferably retain their ordinary cylindrical form and fit closely in a hole in the last, as may be seen from Fig. 5. This structure renders the pin flexible at its middle and pro-
vides room in the last for it to bend, as will be 60 seen. The pin must be $\frac{1}{4}$ or $\frac{5}{16}$ inch in diameter in order to provide sufficient bearing sur-
face in the wood, and such a pin in its ordi-
nary form would be very stiff. The pin 65 which is located in the last part containing the arcuate portion 14 is located off from the center 26 of that portion as shown in Fig. 1. The arcuate portion thus, in effect, constitutes a cam around the pin as "center". As the forepart is swung up about the heel part 70 to the position shown in Fig. 2, the center of the pin 24 moves in the arc 28 about the center 26, whereas the center of the hole in the link 20 in which the pin 24 is mounted moves in the arc 30 about the center of the pin 22. 75 This causes a compressive stress to be exerted on the pins 22 and 24 by tension in the link 20. The reduced portion in the pin 24 is arranged to be on the side of the pin toward which the pull of the link is directed so that when this 80 stress comes on the pin it will bend into the vacant space formed by the cut-away portion and furnish, therefore, a resilient resistance to the collapsing movement which further-
more continually increases during a small 85 movement of the forepart from extended po-
sition, tending therefore to throw the fore-
part back into extended position when slightly displaced therefrom. This resist-
ance, in the construction shown, will increase 90 until the center of the pin 24 has reached the point 32 half way between the center of the pin 24, as shown in Fig. 1 and the point 34 where the two arcs 28 and 30 intersect a 95 second time. After passing the point 32 the tendency of the pin is to throw the last into collapsed position.

The bent condition is shown in dotted lines in Fig. 5. The pin may be initially bent in the reverse direction to make it bind firmly in 100

its pin hole, as explained below in connection with the pin 24^a in Fig. 4.

In Figs. 3 and 4 are shown two different forms of split pins. The pin 24^a in Fig. 3 is formed from a solid pin, holes being bored 5 at 36 and 38 and the slot 40 milled out between them. Fig. 4 shows a pin 24^b which consists of two semi-cylindrical members 42 and 44 cut away on their flat sides as at 46 and also shown as having their longitudinal axes bent 10 about a transverse axis lying in the plane of the slot 46 as shown in Fig. 4. The pin thus formed when driven into a closely fitting cylindrical hole in a last member will hold it- 15 self strongly in position due to the binding ac-
tion brought about by the curvature of the two halves. Since the hole in the last is of the same size as the ends of the pin and the slot 46 is actually milled out of the halves, the pin 20 when reduced to a cylinder by being driven into the hole will still be slotted at its central portion and therefore resilient.

The simplicity and strength of the illustrated construction is manifest. The entire 25 bonding and impositive blocking mechanism consists of only three parts, the two pins and the link. It is cheap to manufacture and simple in operation, as no parts can get out of order with the possible exception of the 30 resilient pin which can easily be replaced if broken.

Having described my invention, what I claim as new and desire to secure by Letters Patent of the United States is:—

1. In a collapsible last, a hinge pin, means 35 for exerting a lateral stress on the pin in collapse, the pin having a notch cut in that side toward which the stress of collapse tends to bend the pin.

2. In a collapsible last having two relatively movable parts, a hinge pin connecting the last parts and having a substantially discontinuously non-uniform cross-section and being arranged to bend under pressure during 40 movement of the last parts.

3. In a collapsible last having two relatively movable parts, a hinge pin connecting the last parts and having a longitudinal flat cut in its side arranged to facilitate a resilient 45 deformation of the pin under the stress of collapse.

4. In a collapsible last having two relatively movable parts, a cylindrical hinge pin connecting the last parts and cut away at a 50 point between its ends arranged to facilitate bending under the stress of collapse.

5. A hinged last having two relatively movable parts one of which parts has a straight hole therein, and a resilient hinge 55 pin in said hole arranged to connect the last parts and to receive a bending stress from the last parts as they move from extended position, said pin having a normally bent portion shorter than said straight hole whereby when 60 said pin is driven into the hole its inherent

resilience will permit its deformation and facilitate binding of the pin in the hole.

6. In a collapsible last, a hinge pin, and a member contacting with the pin and movable relatively to the pin as a whole when the last is collapsed arranged to produce a bending strain in said pin when the last is collapsed, whereby the collapsing movement is resiliently opposed.

7. In a collapsible last, a resilient hinge pin having a notch, and a bonding member 70 co-operating with the pin constructed and arranged to press transversely thereon as the last moves from extreme position, the plane of the bottom of the notch being arranged to be substantially perpendicular to the line of pressure.

8. In a last, a forepart and a heel part 75 constructed and arranged to move relatively to collapse or extend the last, and a resilient hinge pin arranged to receive a bending stress transmitted from the last parts as they move relatively, and to bend substantially under the stress.

9. In a last, a forepart and a heel part constructed and arranged to move relatively to collapse the last, a bonding member uniting the parts, and a resilient pin anchoring 80 said member in a last part, there being space provided in the last to permit substantial distortion of the pin, the last parts and member being constructed to exert a bending stress on the pin as the last starts to collapse, and the pin being arranged to bend substantially under the stress whereby a non-positive lock 85 is produced.

10. A last having a resilient hinge pin, and a forepart and a heel part connected thereby and constructed and arranged to move relatively to collapse or extend the last, 100 and to exert a bending stress on the hinge pin as the last parts move relatively, the last being provided with a space adjacent to the pin to permit bending of the pin under the stress.

11. In a last, a bonding member, a forepart and a heel part connected thereby and arranged to move relatively to collapse or extend the last and to exert stress on the bonding member during such movement, and a resilient hinge pin engaged by the bonding member and arranged to bend under pressure exerted by the bonding member as the last collapses.

12. In a last, a bonding member, a forepart and a heel part connected thereby and arranged to move relatively to collapse or extend the last and to exert stress on the bonding member during such movement, and a resilient hinge pin anchoring the bonding member in a last part and arranged to bend under pressure exerted by the bonding member as the last collapses, there being a space provided in the last in connection with the pin to permit the bending.

13. In a collapsible last, a forepart and a heel part separated by a cut comprising a curve, a bonding member uniting the parts, a pin anchoring the bonding member in that last part which contains the curve, said pin being substantially off the center of said curve, and a pin anchoring the bonding member in the other last part, whereby the collapse of the last exerts a bending stress on the pins, the last having a space to permit substantial bending of one of the pins, said last-named pin being arranged to bend substantially under said stress. 75
14. In a collapsible last, a forepart and a heel part separated by a cut comprising a cam portion, a bonding member uniting the parts, and a resilient pin anchoring the bonding member in that last part which contains the cam portion, said pin being substantially off the center of said cam portion, whereby the collapse of the last exerts a bending stress on the pin, there being also a space provided in the last adjacent to the pin to permit the bending of the pin under the said stress. 80
15. In a collapsible last having two relatively movable parts a resilient hinge pin connecting the last parts and having its flexibility substantially irregularly variable along its length to facilitate bending under stress exerted on the pin by relative movement of the last parts. 85
16. In a last, a hinge pin having its flexibility variable along its length, there being a space provided in the last adjacent to a portion of greater flexibility to permit bending. 90
17. In a collapsible last, a forepart and a heel part arranged for relative movement to collapse and extend the last, and a bonding mechanism connecting said parts constructed and arranged to hold them yieldingly in either their extended or collapsed position, said mechanism comprising a resilient hinge pin, the last being provided with space into which the hinge pin may bend to effect the yielding operation of the bonding mechanism. 100
18. In a collapsible last a hinge pin of non-uniform cross-section mounted in a hole providing a substantial clearance on one side, and means for stressing the pin toward that side in the operation of collapse. 105
19. In a collapsible last, a heel part, a forepart, a bonding member and a distortable hinge pin arranged for relative movement of the last parts in collapse, the last parts and bonding member being arranged to exert stresses substantially opposite in direction upon the hinge pin at substantially separated points, and the last having a space for consequent deformation of the pin. 110
20. A last comprising a toe part and a heel part, a link, and means one of which is resilient for attaching the link to the toe part and the heel part of the last, to hold the last parts against separation. 115
21. A last comprising a toe part and a heel part, a link, and resilient pins for attaching the link to said last parts whereby the two last parts are held against separation. 120
- In testimony whereof I have signed my name to this specification. 125
